UNITED STATES PATENT OFFICE.

JOHN H. BAGNALL, OF RACINE, WISCONSIN, ASSIGNOR OF ONE-HALF TO
HANS P. SWENSEN, OF SAME PLACE.

NECK-YOKE.

SPECIFICATION forming part of Letters Patent No. 506,898, dated October 17, 1893.

Application filed April 10, 1893. Serial No. 469,715. (No model.)

To all whom it may concern:

Be it known that I, JOHN H. BAGNALL, a citizen of the United States, and a resident of Racine, in the county of Racine, and in the 5 State of Wisconsin, have invented certain new and useful Improvements in Neck Yokes; and I do hereby declare that the following is a full, clear, and exact description thereof.

My invention relates to improvements in 10 the construction of neck yokes, and consists in the matters hereinafter described and pointed out in the appended claim.

In the accompanying drawings illustrating 15 my invention: Figure 1 is a side elevation of the central portion of a neck yoke provided with my improvements, and showing parts broken away to better illustrate the construction. Fig. 2 is a cross sectional view of the same taken on line 2-2 of Fig. 1.

20 Referring by letter to the drawings A represents the neck yoke and B the ring secured to the under side of the neck yoke, for engagement with the end of a vehicle pole. It has been common heretofore in order to provide a movable connection for the ring to secure said ring to the under side of the neck yoke by means of two smaller rings arranged adjacent to, and upon opposite sides of the center of the neck yoke and embracing said 25 ring, these small rings being usually engaged with eye-bolts passed through the neck yoke and riveted down upon the upper side of the same. By this construction the lateral play of the pole causes the small rings and the 30 sides of the large ring to continually wear against the under side of the neck yoke and the sides of the pole thereby defacing the surfaces of the neck yoke and pole and where the wear is excessive, materially weakening the pole.

35 40 It is the object of my present invention to provide means for securing the ring B to the under side of the neck yoke in such manner as to be freely movable, and at the same time, to prevent the ring from striking against and defacing the neck-yoke and pole. To this end I provide a suitable housing C having horizontally disposed flanges C' C' arranged to extend longitudinally beneath the neck yoke, and said housing is secured to the neck yoke 45 50 by means of suitable bolts c c extending

through the yoke and engaged with nuts c' c' beneath said flanges. The upper side of the housing is suitably concaved to conform to the shape of the under side of the neck yoke as shown more particularly in Fig. 2. An opening or slot D is made in the under side of the housing for the reception of a loop or eye B' upon the upper side of the ring B and a transverse pivot pin E is engaged in suitable recesses e e within the housing C and is arranged 55 60 to extend across the path of the loop or eye B' and adapted for engagement therewith in the manner shown in the drawings.

In assembling the parts of my device together the loop or eye B' is passed upward 65 through the slot D in the housing C and the transverse pin E slipped through said loop or eye when the ring B is drawn downward so as to bring said transverse pin into engagement with the bearings or recesses e e in the 70 manner shown in Fig. 2. The housing C is then secured to the under side of the neck yoke by means of the bolts or clips c c.

As shown in Fig. 1, I make the slot D of somewhat elongated form so as to permit of 75 a vibrating motion of the contracted portion b between the ring B and the loop or eye B'.

By the described connection of the ring B with the transverse pin E within the housing C a very secure and strong fastening is provided while at the same time the ring B is rendered freely movable upon said pivotal connection. The lower edges of the walls of the housing at the ends of the slot D are so arranged as to limit the vibration of the ring B 85 about the pivotal connection E, so as to prevent said ring from striking against the under side of the neck yoke and the sides of the pole in an obvious manner.

80 85 90 By my improved construction I am enabled to provide a neck yoke center possessing all the advantages gained by a movable connection between the ring and the neck yoke and at the same time so arranged as to effectually prevent the ring from wearing against the 95 under side of the neck yoke and the sides of the pole.

90 95 100 My improved device presents a much more neat and tasty appearance than if the ring B were secured to the under side of the neck

yoke by the smaller rings and eye-bolts in the ordinary manner.

Having thus described my invention, what I claim as new, and desire to secure by Letters 5 Patent, is—

The combination of a neck yoke, provided with a rounded longitudinal groove on its under side, a housing in direct contact with the under side of said neck yoke, and sur-
10 rounding said groove, and provided with hori-
zontally disposed flanges recessed to conform
to the shape of the neck-yoke, bolts extending
through said neck-yoke and said flanges
with retaining nuts beneath the latter, the
15 said housing having a longitudinal slot in
line with the groove in the under side of the
neck-yoke, and transverse recesses and bear-
ings above said slot, a ring having a closed |

loop integral therewith, said loop engaging
with the described groove and slot, and a 20
transverse pin extending loosely through said
loop and resting on said bearings in said re-
cess above said slot, whereby said ring may
have longitudinal movement in said slot and
in the neck-yoke groove, but be prevented 25
from transverse movement, substantially as
set forth.

In testimony that I claim the foregoing I
have hereunto set my hand, at Racine, in the
county of Racine and State of Wisconsin, in 30
the presence of two witnesses.

JOHN H. BAGNALL.
